IRON SHEET PILING

Enno Becker, Bremen, Germany

Application September 4, 1931, Serial No. 561,283
In Germany September 9, 1930

5 Claims. (Cl. 61—60)

It is often the case with sheet piling that parts of the wall are subjected to very great stresses. This is always so if, in addition to the uniformly distributed horizontal forces arising from ground and water pressure, further horizontally or vertically acting forces have to be taken up at different places along the wall, or along short or long sections, of the wall, at regular or irregular intervals.

10 Various methods have been adopted for dealing with the problem of producing walls with different moments of resistance; for instance, it has been proposed to fortify a wall of channel section by introducing iron box sections into the wall, but this has the disadvantage that specially shaped sheets of iron have to be made for taking up the locally greater forces.

15 The present invention avoids this disadvantage; it proceeds to the solution of the problems of easily changing the moments of resistance of the wall and increasing the resistance to additional load by another method.

20 According to the invention sheet piling of groove or channel section is built up of single elements in such manner that the locking device and the construction allow of the linking together of the elements in two different ways.

25 Several constructional forms of the sheet piling according to the invention are shown in the accompanying drawing. In the drawing:

30 Figure 1 indicates a corrugated sheet piling.
Figure 1a illustrates a box-shaped sheet piling.

35 Figure 2 illustrates a corrugated sheet piling with divided connecting members.

Figure 2a illustrates a box-shaped sheet piling with alternate divided and undivided connecting members.

40 Figure 3 illustrates a corrugated sheet piling with alternate divided and undivided connecting members.

Figure 3a illustrates a box-shaped sheet piling with alternate divided and undivided connecting members.

45 Figure 4 illustrates a corrugated sheet piling with divided backs.

Figure 4a illustrates a box-shaped sheet piling with divided backs.

50 Figure 5 illustrates a corrugated sheet piling with alternate divided and undivided backs.

Figure 5a illustrates a box-shaped sheet piling with alternate divided and undivided backs.

According to the constructional form of the invention illustrated in Figure 1, the wall consists

55 of the backs *a* and the connecting members *b*, which when fitted together form a continuous length of channel sheeting with the channel cavities occurring alternately on the two sides of the wall. The backs *a* have their dove-tail grooves which run the length of the sheet of metal at 60 both edges formed with constricted openings (so-called claws), into which the shoulders—likewise dove-tail in cross-section—securely engage along the whole length of the connecting members *b*, so that thus the backs and connecting members are so joined together that they are proof against any pressure or tensional forces that may be exerted.

65 Figure 1a shows a wall built up of the same sections, but the connecting members *b* are fitted in a position obtained by swinging them about a plane normal to the position of the wall, so that thus a wall is obtained of open box sheeting; the channel section however, can, according to Figure 1, at all times be restored by the different 70 disposition of the connecting members *b*, thus with these sections a wall can be constructed which is of channel or box section or a combination of both.

75 In order to ensure an effective moment of 80 resistance of the wall with respect to its axis, the locking parts are held together by any suitable means, which applies to the figures hereinbefore and hereinafter described.

85 To improve the ability of the wall for ramming according to Figures 1 and 1a, all the connecting members *b*, or every alternate one, is divided in the length of the wall and one of the known types of lock is here fitted in place.

90 In the first case, the finished wall produced by building up in channel section, is an open channel piling (Figure 2), and that produced by the box section is an open box piling (Figure 2a), with the unconnected locking parts provided in each connecting member in the length of the 95 wall. In the latter case the finished wall produced by building up in channel section is an open double channel (Figure 3), and that produced by the box section is an open box piling (Figure 3a) with the unconnected, locking parts in every 100 second connecting member in the length of the wall. It will be understood that a larger number of undivided connecting members may be employed before the use of a divided connecting member; thus walls are produced which are built up of backs and connecting members and in which channel and box sections may alternate by the way of plates.

105 The wall shown in Figure 1 may be divided in 110

such manner that instead of the connecting members *b* being divided it is the backs *a* which are divided, they being connected again by one of the known types of lock; all the rear sections *a* 5 may in such case be divided, or only every alternate one.

In the first case the finished wall produced by building up in channel section is an open channel piling (Figure 4), and that produced by the box 10 section is an open box piling (Figure 4a) with the unconnected locking parts provided in each back *a*. In the latter case, the finished wall produced by building up in channel section is an open channel piling (Figure 5) and that produced by 15 the box section is an open box piling (Figure 5a) with the unconnected locking parts in every second back *a*, that is to say only on the outside of the wall or only on the inside of the wall.

The examples hereinbefore described show that 20 with the iron sheet piling built up from separate parts it is possible to produce walls by so providing and combining the parts that the connecting members *b* can be jointed about an axis normal to the plane of the wall moved through 25 the same angle, the walls consisting only of open channel section or only of open box section or of both channel and box section together in any desired arrangement, so that either single sheeting, double sheeting or whole walls can be rammed.

30 The invention hereinbefore described has the advantage that the parts can be very simply produced in any rolling mill and assembled very readily in accordance with the requirements at the point of assembly, that is to say, they readily adapt themselves to local conditions. Furthermore every thickness of wall and therefore every moment of resistance, however great, can be attained for channel and box section of walls, as all the parts need only a small incision in the rollers 35 and thus no account need be taken of the diameter of the rollers provided. Furthermore a considerable practical advantage is that the walls are uniform in thickness independently of whether the sheeting is of channel section or whether it is of 40 box section or both together.

I claim:

1. Iron sheet piling composed of two sets of substantially flat irons, namely backs and connecting elements, the backs being arranged parallel to the axis of the wall and the connecting elements transversely thereto, both sets of irons being provided at their ends with symmetrical locking parts consisting of grooves and tongues 50

the grooves being arranged at the same side of the back irons while the tongues are disposed on opposite sides of the connecting elements, the two sets of irons being connected by said locking parts so as to form a pile wall with a channel section. 80

2. Iron sheet piling composed of two sets of substantially flat irons, namely backs and connecting elements, the backs being subdivided into two interlocking portions arranged parallel to the axis of the pile wall while the connecting elements are disposed in an oblique direction thereto, both sets of irons being provided at their ends with symmetrical locking parts, consisting of grooves and tongues the grooves being arranged at the same side of the back iron while the tongues are disposed on opposite sides of the connecting elements. 85

3. Iron sheet piling composed of two sets of substantially flat irons, namely backs and connecting elements, the connecting elements being subdivided into two interlocking portions arranged substantially perpendicularly to the axis of the pile wall while the backs are disposed parallel thereto, both sets of irons being provided at their ends with symmetrical locking parts consisting of grooves and tongues the grooves being arranged at the same side of the back irons while the tongues are disposed on opposite sides of the connecting elements. 90

4. Iron sheet piling composed of two sets of substantially flat irons, namely backs and connecting elements, the backs being arranged parallel to the axis of the wall and the connecting elements transversely thereto, both sets of irons being provided with symmetrical locking parts which are arranged at the same side of the back irons and at opposite sides of the connecting elements. 100

5. Iron sheet piling composed of two sets of substantially flat irons, namely backs and connecting elements, the backs being arranged parallel to the axis of the wall and the connecting elements transversely thereto, the backs being provided with locking grooves having a level and reinforced part on either side of the groove while the connecting elements are provided with tongues disposed on opposite sides, for which purpose the ends of the connecting elements are offset thereby forming shoulders which have a level 115 surface cooperating with one of the said level parts of the backs. 120
